UNITED STATES PATENT OFFICE.

CHARLES A. ROLFE, OF ST. PAUL, MINNESOTA.

SHIRT-CUFF.

1,360,687.

Specification of Letters Patent. Patented Nov. 30, 1920.

Application filed March 8, 1917. Serial No. 153,455.

To all whom it may concern:

Be it known that I, CHARLES A. ROLFE, a citizen of the United States, resident of St. Paul, county of Ramsey, State of Minnesota, have invented certain new and useful Improvements in Shirt-Cuffs, of which the following is a specification.

My invention relates to the cuffs of garments and particularly to shirt cuffs, and the object of my invention is to provide an improved cuff from which it will be impossible to lose the cuff button, particularly when the sleeves are unbuttoned and partly rolled up.

Other objects of the invention will appear from the following detailed description.

The invention consists generally in various constructions and combinations, all as hereinafter described and particularly pointed out in the claim.

In the accompanying drawings forming part of this specification,—

Figure 1 is a plan view of a shirt cuff embodying my invention,

Fig. 2 is a view of the cuff showing a cuff-button inserted,

Fig. 3 is a sectional view of the cuff, showing the position of the cuff-button.

In the drawing, 2 represents a portion of a shirt sleeve to which is attached a cuff 3, said cuff being of the so-called "French" or "soft" variety and therefore unstarched. In wearing this type of cuff same is adapted to be folded back along the center line 4, while the two button-holes 5 are provided therein at each end equidistant from the center line 4. When the cuff is folded along the line 4 and the ends brought together for fastening, the button-holes 5 are all brought into line so that a cuff-button 6 may be readily inserted therethrough. I have found, however, that cuff-buttons are frequently lost from cuffs of this type, as the smaller head of the cuff-button often pulls

through the button-holes, especially when the latter are somewhat worn, so that the shank of the cuff-button has considerable play therein. To overcome this danger of losing cuff-buttons I provide a tongue or flap 7, either stitched to or made integral with the cuff 3. Said tongue is preferably located opposite one of the inner button-holes, as shown in Fig. 1, and is provided with a button-hole 8. The tongue 7 is folded over on the inside of the cuff, as shown in Fig. 2, and the cuff-button inserted through the button-holes 5 in that end of the cuff and the button-hole 8. The button-hole 8 is preferably smaller than the button-holes 5 and the tongue 7 is so constructed that when a cuff-button is inserted through the button-holes, the tongue 7 draws the shank of the cuff-button tightly against the ends of the button-holes 5, while the opposite end of the button-hole 8 presses tightly against said shank. Thus, as shown in Fig. 3, the material of the cuff entirely surrounds the shank and is held firmly against it on all sides, absolutely preventing the loss of the cuff-button when the cuffs are unbuttoned and partially rolled up.

I claim as my invention:

A shirt cuff having button holes therein and a tongue adapted to fold around the end of the cuff and having a buttonhole therein, said tongue lying between the folds of the cuff and the outer end of the buttonhole therein lapping the corresponding end of the adjacent buttonhole in the cuff only a sufficient distance to receive the shank of the cuff button between the outer end wall of the buttonhole in the cuff and outer end wall of the buttonhole in the tongue, whereby the button will be locked at one end of the buttonhole in the cuff.

In witness whereof, I have hereunto set my hand this 28th day of February, 1917.

CHARLES A. ROLFE.
